CRUSHING AND/OR GRINDING APPARATUS

Samuel Richard Tonkin, Salisbury, Southern Rhodesia

Application June 11, 1934, Serial No. 729,937
In Great Britain June 28, 1933

6 Claims. (Cl. 83—53)

This invention relates to crushing and/or grinding apparatus and has for its object to provide a simple, robust and efficient apparatus for this purpose.

5. According to my invention the apparatus comprises two surfaces, between which the material is adapted to be crushed and/or ground, one such surface being adapted for substantially reciprocating vertical movement, or a combination of 10 such reciprocatory and other movement, and the other constituting an anvil surface, the said movement being effected by the centrifugal action of a rotating mass having its centre of gravity eccentric to its axis of rotation.
15. A crushing or grinding mill made according to the present invention comprises a roller mounted for rotation with a shaft, and an anvil block in association therewith. The rotation of a mass mounted on the shaft and having its centre of 20 gravity eccentric to the axis of the shaft, causes the said crushing roller to rise and fall, and thereby crush or grind the material between the surfaces.

A preferred embodiment of my invention will now be described with reference to the accompanying drawing wherein:

Fig. 1 is a diagrammatic side elevation of the apparatus;

Fig. 2 is an end elevation of Fig. 1 looking in the direction of the arrow;

Fig. 3 is a detail view of a modification;

Fig. 4 is a diagrammatic side elevation of the mechanism additional to that shown in Figs. 1—3, for imparting endwise movement to the shaft;

Fig. 5 is an end view of part of the mechanism shown in Fig. 4.

Like reference numerals indicate corresponding parts in all the figures.

40 Referring now to the drawing, the apparatus broadly comprises a crushing or grinding roller 1 fixedly mounted on a shaft 2 and adapted for rotation therewith, and an anvil block 3 in association with the said roller 1. A disc 4 is fixedly mounted on the shaft 2 and is provided with a mass 5 positioned near the periphery thereof.

The shaft 2 is mounted in bearings 7 and 8 in such a manner as to allow for a degree of vertical movement of the said shaft. The bearing 7 is positioned at that end of the shaft near the crushing roller 1, and the bearing 8 near the opposite end of the shaft. A guide frame 9 allows the bearing 7 and the adjacent end of the shaft 2 to slide up and down in a vertical direction, but 55 prevents any movement in a lateral direction.

The bearing 8 is of any suitable known self-aligning type (no detailed description of which is here deemed necessary) the arrangement being such as to permit a limited degree of rocking movement. The rotatable shaft 2 is driven by 5 means of the driving pulley 11 keyed or otherwise secured to the shaft 2, and driven by any suitable means.

The anvil surface of the block 3 is preferably shaped to conform substantially with the peripheral surface of the crushing roller.

The unbalanced mass 5 is secured to the disc 4 by means of bolts or studs 12 passing through holes 13 provided on the disc, the arrangement being such that the mass 5 can be secured at 15 any position on the outer face of the disc and thereby permit different portions of the peripheral surface of the roller to be brought into contact with the material on the anvil.

A chute 14 is positioned on the feeding side of 20 the crushing roller the rotation of the said roller thus tending to feed the material to be crushed between the roller and the anvil block, the ground material being discharged with some force from the opposite side of the anvil block immediately 25 it is crushed or ground. The rotation of the roller causes the treated material to be thrown clear of the anvil block.

The apparatus may be supported on concrete 30 foundation blocks 17 and 18.

In a modification shown in Fig. 3, the bearing 7 and its associated guides 9 are dispensed with and a similar effect obtained by the use of a strap 20 surrounding the shaft 2 and arm 21, the outer end of which is carried by and supported in an L shaped bracket 22 fixed to the foundation block 17 the arrangement being such as to provide a substantially vertical reciprocatory movement to that end of the shaft adjacent the roller 1.

When desired a lateral endwise movement may be imparted to the shaft 2 by the addition of a mechanism as shown by way of example in Figs. 4 and 5.

The device illustrated comprises discs 30, 31, and 32 through which the shaft 2 is adapted to slide freely. The disc 32 supports the outer ends of two guide bars 33 the opposite ends of the guide bars passing through the fixed bearing 8 of the shaft 2. The outer ends of the bars 33 may be 50 shouldered and screwed and provided with nuts 34. A collar 35 is fixed to or provided on the shaft between the discs 30 and 31. A helical spring 36 tends to maintain the disc 35 and shaft in their normal position. Endwise movement is imparted 55

to the collar 35 and consequently to the shaft by toggle mechanism comprising arms 36 and link 37. The link 37 is pivotally mounted on a pin 38 eccentrically disposed on the face of the ratchet wheel 39. Ratchet wheel 39 is adapted to be intermittently rotated by the operation of a pawl 40 the latter being rigidly mounted on one end of a pivot rod 41, the opposite end of which is bent to define a rocking arm 42 which is rocked 10 at each revolution of the driving pulley 11 by means of the pin 43 eccentrically mounted on the circular face of the driving pulley 11. The rocking arm 42 is returned to its normal position after each oscillation by means of spring 44, the 15 outer end of which is secured to a fixed pin 45. From the above construction it will be seen that each revolution of the driving pulley causes the pawl 40 to rotate the ratchet wheel 39 an angular distance equal to the pitch of the ratchet wheel 20 with a result that the arms 36 of the toggle tend to align, complete alignment taking place during the time the ratchet wheel has made a complete revolution. The endwise movement of the shaft is thus effected by the displacement of the members 36 of the toggle, the outer end of one member bearing against the fixed bearing and the outer end of the other member against the disc 30 to move the collar 35 and consequently the shaft in an endwise direction.

30 When the link 37 is raised or lowered, the spring 36 tends to move the collar 35 and consequently the shaft towards the right to its normal position.

While I have found the above mechanism suitable for imparting endwise movement to the shaft, I wish it to be understood that any other suitable and known mechanism may be employed for a like purpose, for example the toggle links may be dispensed with and two corrugated engaging 40 surfaces may be employed one of which is adapted to ride upon the other by reason of the rotation of the pulley to give a like effect.

The roller shaft and other parts may be formed of any suitable material, but in practice I have 45 found a shaft formed of wood for example oak or ash to be preferable, although a metallic shaft may also be used.

In operation the material to be crushed is fed into the chute 14 and is carried between the roller 50 1 and anvil surface 3 by the rotation of the roller, the crushing and grinding operation of the material being effected by reason of the relative movement of the roller 1 and anvil surface 3 the former being reciprocated vertically by reason 55 of the rotation of the unbalanced mass 5 secured to the disc 4 and rigidly mounted on the shaft 2, endwise reciprocating movement being in some cases imparted to the shaft by a suitable additional mechanism.

60 What I claim and desire to secure by Letters Patent is:—

1. Crushing and grinding apparatus comprising an anvil surface, a crushing roller positioned over the anvil surface and between which, and the said anvil surface the material is adapted to be crushed, a shaft adapted for rotation mounted above said anvil surface to support the crushing roller, an eccentric mass carried by said shaft and having its centre in spaced relation to the axis 65 of the said shaft, two bearings supporting the said shaft one being a self-aligning bearing adjacent the driving end of the shaft, and the other being defined by a pair of guides which permit a degree of vertical movement of that end of the shaft 70 remote from the said self-aligning bearing, that

part of the said shaft carrying the crushing roller being adapted to reciprocate by the centrifugal action of the said eccentric mass.

2. Crushing and grinding apparatus comprising an anvil surface, a crushing roller positioned over the anvil surface and between which, and the said anvil surface the material is adapted to be crushed, a shaft adapted for rotation mounted above said anvil surface to support the crushing roller, an eccentric mass carried by said shaft and having its centre in spaced relation to the axis of the said shaft, two bearings supporting the said shaft one being a self-aligning bearing adjacent the driving end of the shaft, and the other being defined by a pair of vertical guides which permit a degree of vertical movement of that end of the shaft remote from the said self-aligning bearing, that part of the said shaft carrying the crushing roller being adapted to reciprocate by the centrifugal action of the said eccentric mass. 20

3. Crushing and grinding apparatus comprising an anvil surface, a crushing roller positioned over the anvil surface and between which, and the said anvil surface the material is adapted to be crushed, a shaft adapted for rotation mounted above said anvil surface to support the crushing roller, an eccentric mass carried by said shaft and having its centre in spaced relation to the axis of the said shaft, two bearings supporting the said shaft one being a self-aligning bearing adjacent the driving end of the shaft, and the other being defined by a pair of vertical guides which permit a degree of vertical movement of that end of the shaft remote from the said self-aligning bearing, that part of the said shaft carrying the crushing roller being adapted to reciprocate by the centrifugal action of the said eccentric mass. 30

4. Crushing and grinding apparatus comprising an anvil member, a recess in the anvil member, a crushing roller adapted to co-operate with the said recess to crush the material, a shaft adapted for rotation mounted above said anvil surface to support the crushing roller, an eccentric mass carried by said shaft and having its centre in spaced relation to the axis of the said shaft, two bearings supporting the said shaft one being a self-aligning bearing adjacent the driving end of the shaft, and the other being defined by a pair of guides which permit a degree of vertical movement of that end of the shaft remote from the said self-aligning bearing, that part of the said shaft carrying the crushing roller being adapted to reciprocate by the centrifugal action of the said eccentric mass. 40

5. Crushing and grinding apparatus comprising an anvil member, a recess in the anvil member, a crushing roller adapted to co-operate with the said recess to crush the material, a chute adapted for delivering material to be crushed into the said recess, a shaft adapted for rotation mounted above said anvil surface to support the crushing roller, an eccentric mass carried by said shaft and having its centre in spaced relation to the axis of the said shaft, two bearings supporting the said shaft one being a self-aligning bearing adjacent the driving end of the shaft, and the other being defined by a pair of guides which permit a degree of vertical movement of that end of the shaft remote from the said self-aligning bearing, that part of the said shaft carrying the crushing roller being adapted to reciprocate by the centrifugal action of the said eccentric mass. 50

the centrifugal action of the said eccentric mass.
6. Crushing and grinding apparatus comprising
an anvil surface, a crushing roller positioned over
the anvil surface and between which, and the said
5 anvil surface the material is adapted to be
crushed, a shaft adapted for rotation mounted
above said anvil surface to support the crushing
roller, an eccentric mass carried by said shaft and
having its centre in spaced relation to the axis of
10 the said shaft, two bearings supporting the said
shaft one being a self-aligning bearing adjacent

the driving end of the shaft, and the other being
defined by a pair of guides which permit a degree
of vertical movement of that end of the shaft re-
mote from the said self-aligning bearing, means
associated with the said shaft for producing an 5
endwise motion of said crushing roller, that part
of the said shaft carrying the crushing roller being
adapted to reciprocate by the centrifugal action
of the said eccentric mass.
